UNITED STATES PATENT OFFICE

PAUL G. PEIK, OF CHICAGO, ILLINOIS

LAMP

Application filed May 31, 1927. Serial No. 195,563.

My invention relates to improvements in lamps, and it consists in the combinations, constructions, and arrangements herein described and claimed.

5 An object of my invention is to provide a lamp of the acetylene type which is especially adapted to be used by miners, but which may be used efficiently as a railroad lamp.

A further object of my invention is to provide a device of the type described which has a uniform generation of gas by providing a novel means for the uniform flow of water to the carbide.

15 A further object of my invention is to provide a device of the type described in which the amount of water passing into the carbide may be varied or shut off at will.

20 A further object of my invention is to provide a device of the type described which is simple in construction, easy to assemble, durable and efficient for the purpose intended.

Other objects and advantages will appear in the following specification, and the novel features of the invention will be particularly 25 pointed out in the appended claims.

My invention is illustrated in the accompanying drawings, forming part of this application, in which

30 Figure 1 is a vertical sectional view of my device, parts thereof being shown in elevation, and

Figure 2 is a sectional view of a modified form of my device.

In carrying out my invention, I provide a 35 casing 1 having a lens 2 removably secured thereto by a retainer ring 3. A burner 4 is disposed in the casing 1 and is provided with a hollow tubular portion 5 which extends therethrough.

40 A cylindrical body portion 6 is rigidly secured to the casing 1 as at 7 and is provided with a lower threaded portion 8 and an upper threaded portion 9. A carbide receptacle 10 is provided with a threaded portion 11 at the

45 open end thereof which is receivable in the threaded portion 8 of the body portion 6. A felt pad 12 is disposed in the body portion 6 and conforms to the inner wall thereof. The felt pad 12 is held adjacent the tubular portion 5 of the burner 4 by a metal retainer 12'

which is disposed adjacent the upper extremity of the carbide receptacle 10.

An overflow tank 13 is provided with a threaded portion 14 which is receivable by the threaded portion 9 of the body portion 6. 55 An auxiliary water tank 15 is centrally disposed in the overflow tank 13 and is provided with circumferentially-disposed openings 16 spaced equal distances from the bottom 17 of the overflow tank 13. A tube 18 is centrally disposed in the bottom 17 and extends from a point a short distance above the openings 16 to a point a short distance from the bottom of the carbide receptacle 10. A wick 19 is disposed in the tube 18 and extends downwardly to a point substantially adjacent the lower extremity thereof. The upper portion of the wick extends over the upper extremity of the tube 18 and downwardly upon the outside of the tube for a short distance into the 60 auxiliary water tank 15.

A further object of my invention is to provide a device of the type described which is simple in construction, easy to assemble, durable and efficient for the purpose intended.

The main water tank 20 is provided with a threaded portion 21 which is receivable in the threaded portion 9 of the body portion 6. An opening 22 is provided for the water tank 75 20 for pouring water 23 therethrough into the main water tank 20. A cap 24 is provided for the opening 22.

A water check valve 25 extends through the main water tank 20 and is adapted to engage 80 with a valve seat 26 which provides communication from the main water tank 20 to the auxiliary water tank 15. The valve 25 is provided with a threaded portion 27 which extends through threads 28 of the tank 20. A 85 shut-off valve 29 extends through the water tank 20 and is provided with a disc-shaped head portion 30 adapted to be moved into engagement with the upper extremity of the wick 19. A threaded portion 31 is provided 90 for the valve 29 and extends through a threaded portion 32 in the tank 20. Hand wheels 33 and 34 are provided for the valves 25 and 29, respectively.

From the foregoing description of the various parts of the device, the operation thereof may be readily understood.

The water tank 20 is first filled with water and the water check valve 25 is adjusted to the approximate position for permitting the 100

desired amount of water to pass from the water tank. Before igniting the gas from the burner, the operator makes sure that the auxiliary tank 15 has the desired amount of water therein. The wick 19 is so constructed that it will permit only a desired amount of water, i. e., the amount required by the burner, to pass therethrough at a uniform rate and into the carbide container. As the water passes from the wick and drops upon the carbide, a gas is formed which passes through the burner 4. This gas may be ignited by any suitable means, not shown.

The uniform passage of the water down the wick is dependent upon maintaining a uniform level of the water in the auxiliary tank. Therefore, the wall of the auxiliary tank 15 is disposed relatively close to the wick 19, whereby the desired amount of water will be supplied to the wick, irrespective of the position at which the lamp is held. The flow of the water through any mechanical valve, such as 26, is increased through any shaking of the lamp which occurs when in use. This additional amount of water passes off through the openings 16, thus maintaining a uniform level of the water desired and necessary for the uniform passage of water down the wick. The overflow tank 13 is sufficient to receive all the excess water which may pass through the openings 16.

Should the operator wish to shut off entirely the supply of water to the wick, the shut-off valve 29 may be moved downwardly, thus holding that portion of the wick which extends over the upper end of the tube 18 in close engagement with the tube.

In Figure 2, I have shown a modified form of the water-feeding mechanism which is composed of a water tank 40 having a tube 41 extending through the bottom thereof and a carbide container 42 which is removably secured to the water tank 40. A wick 43 extends through the tube 41 and over the upper edge thereof. A water check valve 44 is movably disposed within the upper wall of the water tank 40 and is adapted to be moved into engagement with the wick 43 for varying the amount of water passing through the wick and cutting off the entire passage of the water through the wick, if desired. A burner, indicated generally at 45, is disposed in communication with the carbide container 42.

I claim:

1. A device of the type described comprising a carbide chamber for containing carbide, a liquid tank adapted to contain a liquid, a wick, a receptacle for said wick extending into said carbide chamber, one end of said wick extending over said wick receptacle, and means adapted to be moved into engagement with the end of said wick for

varying the amount of liquid passing therethrough.

2. A device of the type described comprising a body portion, an over-flow tank disposed in said body portion, an auxiliary liquid tank disposed in said over-flow tank, a main liquid tank having a portion receivable in said body portion adjacent said auxiliary tank and said over-flow tank, a carbide container having a portion receivable in said body portion, a wick, a wick receptacle disposed in said auxiliary tank and extending into said carbide container, one end of said wick extending over said wick receptacle, means for varying the amount of liquid passing from said main liquid tank into said auxiliary liquid tank, and means adapted to be moved into engagement with the end of said wick for varying the amount of the liquid passing through said wick.

3. A device of the type described comprising a carbide container, a main liquid tank, an auxiliary liquid tank disposed between said main liquid tank and said carbide container, means for directing a predetermined amount of liquid from said main liquid tank into said auxiliary tank, an overflow tank, means providing communication between said auxiliary tank and said overflow tank for maintaining the liquid in said auxiliary tank at a predetermined height, and means communicating with said auxiliary tank for directing the liquid at a predetermined rate of speed into said carbide container.

4. A device of the type described comprising a carbide container, a main liquid tank, an auxiliary liquid tank disposed between said main liquid tank and said carbide container, means for directing a predetermined amount of liquid from said main liquid tank into said auxiliary tank, an overflow tank, means providing communication between said auxiliary tank and said overflow tank for maintaining the liquid in said auxiliary tank at a predetermined height, means communicating with said auxiliary tank for directing the liquid at a predetermined rate of speed into said carbide container, said means comprising a wick-receiving member, and a wick disposed in said wick-receiving member and having a portion extending over said wick-receiving member and beneath the level of the liquid in said auxiliary tank, whereby the liquid will be drawn through said wick into said carbide container.

5. A device of the type described comprising a cylindrical body portion, an overflow tank disposed in said body portion, an auxiliary tank disposed in said overflow tank, a main liquid tank arranged to contain a liquid having one end disposed in said body portion in engagement with said overflow tank and said auxiliary tank, means for varying the flow of the liquid from said main liquid tank into said auxiliary tank, and means

whereby the liquid in said auxiliary tank may be maintained at a predetermined level, said means directing additional liquid from said auxiliary tank into said overflow tank.

5 6. A device of the type described comprising a cylindrical body portion, an overflow tank disposed in said body portion, an auxiliary tank disposed in said overflow tank, a main liquid tank arranged to contain a liquid 10 having one end disposed in said body portion in engagement with said overflow tank and said auxiliary tank, means for varying the flow of the liquid from said main liquid tank into said auxiliary tank, means whereby the 15 liquid in said auxiliary tank may be maintained at a predetermined level, said means directing additional liquid from said auxiliary tank into said overflow tank, a wick container extending into said auxiliary tank 20 and having one end positioned above the liquid therein, and a wick disposed in said wick container and having a portion extending over the upper edge of said wick container and into the liquid in said auxiliary tank 25 for directing the liquid through said wick.

7. A device of the type described comprising a cylindrical body portion, an overflow tank disposed in said body portion, an auxiliary tank disposed in said overflow tank, a main liquid tank arranged to contain a liquid having one end disposed in said body portion in engagement with said overflow tank and said auxiliary tank, means for varying 30 the flow of the liquid from said main liquid tank into said auxiliary tank, means whereby the liquid in said auxiliary tank may be maintained at a predetermined level, said means directing additional liquid from said auxiliary tank into said overflow tank, a wick container extending into said auxiliary tank and having one end positioned above the liquid therein, a wick disposed in said wick container and having a portion extending 35 over the upper edge of said wick container and into the liquid in said auxiliary tank for directing the liquid through said wick, and means arranged to be moved into engagement with the portion of said wick extending over 40 the end of said wick container for varying the flow of the liquid through said wick.

8. A device of the type described comprising a cylindrical body portion, an overflow tank disposed in said body portion, an auxiliary tank disposed in said overflow tank, a main liquid tank arranged to contain a liquid having one end disposed in said body portion in engagement with said overflow tank and said auxiliary tank, means for varying the flow of the liquid from said main liquid tank into said auxiliary tank, means whereby the liquid in said auxiliary tank may be maintained at a predetermined level, said means directing additional liquid from said auxiliary tank into said overflow tank, a wick 55

container extending into said auxiliary tank and having one end positioned above the liquid therein, a wick disposed in said wick container and having a portion extending over the upper edge of said wick container and into the liquid in said auxiliary tank for directing the liquid through said wick, means arranged to be moved into engagement with the portion of said wick extending over the end of said wick container for varying the flow of the liquid through said wick, and a carbide container having one end disposed in said body portion and arranged to receive a carbide. 70 75
